BOX NAILING MACHINE

Grover C. Cable, Huntington Park, Calif.

Application September 8, 1951, Serial No. 245,694

15 Claims. (Cl. 1—8.1)

1

My invention relates to box nailing machinery, and more particularly, to an improvement therein for accurately registering work pieces to be nailed together in proper nailing position. Though my invention may also be applied to the manufacture of boxes, and to the manufacture of laminated panels, and to the lidding of boxes, it is described herein with particular reference to the manufacture of pallets.

Pallets of the type with reference to which my invention is particularly described herein comprise a plurality of joints to which a plurality of interconnecting cross-boards are nailed. Such a pallet is employed to form a side, or the floor, of a box or crate.

In the use of box nailing machinery in the manufacture of such pallets, the joists and the cross-boards are usually assembled in intersecting relationship in a jig, and the jig is advanced along a track to a position where the joists and cross-boards to be nailed together register in nailing position with box nailing members which are employed to punch the nails into the intersecting portions of the joists and cross-boards. For convenience herein the joists and cross-boards are sometimes referred to more broadly as work pieces to emphasize the fact that the use of my invention is not limited to the manufacture of pallets.

In practice, it is found that the registering of the intersecting work-pieces in nailing position consumes considerable time, it being common to move the jig back and forth along the track in an attempt to adjust it to registering position by eye. This time-consuming element of the nailing operation is eliminated in accordance with my invention by means of a simple, low-cost, reliable, automatic registering mechanism in the form of accessories that may be readily attached to present box nailing machines.

An object of my invention is to provide an improved nailing machine in which a pair of superposed work pieces are automatically and accurately registered in nailing position when advanced along a track.

Another object of my invention is to provide a nailing machine with a stop which automatically registers superposed work pieces in proper nailing position with means for withdrawing this stop after the nailing operation and for cocking a trigger that returns the stop to operating position when another pair of superposed work pieces is advanced toward nailing position.

Another object of my invention is to provide an improved means for operating and withdrawing a registering stop from a track along which

2

pairs of work pieces are fed into nailing position, which means is easily adjusted in accordance with the track width.

Other objects and advantages of my invention will become apparent from the following specification when read in connection with the accompanying drawings, in which:

Fig. 1 is a front elevational view of a nailing machine incorporating registering accessories in accordance with my invention;

Fig. 2 is a fragmentary sectional view showing a portion of those accessories taken on the line 2—2 of Fig. 1;

Fig. 3 is a fragmentary isometric view showing details of the registering mechanism with the nailing members in raised position;

Fig. 4 is a fragmentary sectional view taken on the line 2—2 of Fig. 1 showing the nailing members in lowered position after completion of a nailing operation;

Fig. 5 is a fragmentary sectional view illustrating the action of the cam bar taken on the line 5—5 of Fig. 3.

Fig. 6 is a fragmentary sectional view of the detent lock taken on the line 6—6 of Fig. 3;

Figs. 7—8 are fragmentary sectional views taken on the line 7—7 of Fig. 3 illustrating the operation of the registering mechanism as a pallet is advanced along the track to nailing position;

Fig. 9 is a fragmentary detailed plan view of an alternative form of stop;

Fig. 10 is a sectional view of the alternative form of stop taken on the line 10—10 of Fig. 8;

Fig. 11 is a fragmentary plan view of an alternative form of stop release mechanism;

Fig. 12 is a fragmentary sectional view of the alternate stop release mechanism taken on the line 12—12 of Fig. 10;

Fig. 13 is a perspective view of a jig employed in making pallets in accordance with my invention; and

Fig. 14 shows the jig with the pallet in place after nailing.

Referring to the drawings, and particularly to Fig. 1, there is illustrated a nailing machine of the type to which my invention has been applied, only so much of the nailing machine being illustrated and described as is necessary to an understanding of my invention. This particular nailing machine is commonly employed for making boxes, pallets and laminated panels, and also for lidding boxes and for other purposes.

The nailing machine comprises a pair of upright members 20 between which a horizontal track 22 is mounted. The bed 26 of the track

22 is secured to the upper side of a cross-bar 24 and is also supported by other means (not shown) so as to maintain the bed horizontal. The track 22 also comprises a pair of parallel rails or guides 23 in the form of angle bars having their horizontal sections 29 secured by bolts 30 to the bed 26 with their vertical sections 31 extending upwardly from the bed 22. The angle bars 23 extend horizontally perpendicular to the plane of the uprights 28 and are adjustably positioned upon the bed 26 to accommodate work of different widths. The vertical sections 31 act as guide bars to feed work accurately into position.

A jig 40 is usually employed in making a pallet with this nailing machine, the design of the jig depending upon the size and type of pallet to be made. In the particular form of jig 40 illustrated in Fig. 13 three base boards 42 are interconnected by two pairs of cross-bars 44, 45 and 46, 47, at opposite ends thereof, the jig being of rectangular configuration. In order to assure accurate guiding of the jig along the track 22, the outer edges 43 of the outer base boards 42 are spaced apart a distance just slightly less than the spacing between the guide bars 31. However, for reasons which will become apparent hereinafter, the cross-bars 44, 45, 46 and 47 are of a length less than the distance between the guide bars 31 and the outer ends of these cross-bars are spaced inwardly from the outer edges 43 of the jig 40. The outer cross-bars 44 and 46 are of less height than the inner cross-bars 45 and 47, and the inner cross-bars 45 and 47 are provided with staples 59 to aid in assembling cross-pieces from which a pallet is to be made.

In making a pallet, a front joist 52 is placed between the front pair of cross-bars 44 and 45, these cross-bars being spaced apart a distance just sufficient to accommodate the front joist readily. Similarly, a rear joist 54 is placed between the rear pair of cross-bars 46 and 47, these cross-bars also being spaced apart a distance just sufficient to accommodate the rear joist readily. Both joists 52 and 54 are longer than the cross-bars 44, 45, 46 and 47, each having a length equal to the width of the jig 40. The ends of the joists are aligned with the edges 48 of the jig 40. A plurality of front- or side-boards 58 are then laid in predetermined positions upon the joists extending perpendicular thereto in intersecting relationship therewith, the positions of the boards 58 being established by the staples 59.

To nail the joists 52 and 54 and the boards 58 together to complete the pallet, the jig 40 is advanced from the rear of the nailing machine to the front in the direction indicated by the arrow 60 in Figs. 7 and 8, with the joists 52 and 54 perpendicular to the axis of the track and the boards 58 parallel to the axis of the track.

Two stops 62 in the form of cylindrical pins are movable laterally through openings 64 in the guide bars 31 between inner, or operative, positions, as indicated in Fig. 8 and outer, or inoperative, positions, as indicated in Fig. 7. When the stops 62 are in their inner, or operative, positions, they are in position to engage the front faces of the joist 52 or 54 to limit the advancement of the jig 40 along the track and to halt the joist so engaged in nailing position just behind the stops 62. But when the stops 62 have been withdrawn to their outer, or inoperative, positions, the joists may be advanced past the nailing position. The remainder of the registering mechanism, which is employed to automatically move the stops inwardly and outwardly of the track between their

operated and withdrawn positions, are described in detail hereinafter.

The nailing of the work pieces, that is joists 52 and 54 and cross-boards 58, with the machine here illustrated is accomplished by means of a pair of horizontal nailing members 66 and 68 mounted on the uprights 28 for vertical reciprocation relative to the track 22, the nailing members being successively lowered by mechanical means (not shown) to force nails into the intersecting work pieces. More particularly, the lower nailing member, or chuck-supporting bar, 66 carries a plurality of nail chucks 70 which are individually supplied nails from a nail pan 71 through nail tubes 72. The chucks 70 are adjustable forwardly and rearwardly in a horizontal line transverse of the chuck-supporting bar 66 in order that the nails may be nailed into the joists either along a straight line or in staggered relation as desired. The upper nailing member or nailing bar 68 carries a plurality of nailing rods 74 which are adapted for reciprocation in channels (not shown) in the chucks 70 to force nails out of the bottoms of the chucks.

In the operation of the nailing machine, when it is desired to nail cross-boards to a joist which has been placed in nailing position, a foot clutch pedal (not shown) is pressed, putting into operation a mechanism which lowers the chuck-supporting bar 66 to bring the chucks 70 into contact with the upper surfaces of the boards 58 and also lowers the nail-driving bar 68 while the chucks are in such contact to force the nailing rods 74 downwardly, pressing the nails through the boards 58 into the particular joist 52 or 54 that is in nailing position. The two nailing members 66 and 68 then return automatically to their normal elevated positions quickly, and nails are fed through the tubes 72 into the chucks 70 preparatory for the next nailing operation.

In accordance with my invention the stops or registering pins 62 normally project inwardly of the guide bars 31, as indicated in Fig. 8, being secured to the rear ends of flat leaf springs 76 that are secured at their front ends to the guide bars. The front ends of the leaf springs 76 are attached to the guide bars 31 by means of screws 78 and the stops 62 are provided with reduced threaded portions 82 at their outer ends which reduced portions project through the leaf springs to engage lock nuts 84 for securing the stops in place on the leaf springs 76. The leaf springs 76 lie in vertical planes normally urging the stops 62 into their inner or operative positions and normally lying adjacent to though spaced slightly from the vertical guide plates 31. The rear ends of the leaf springs 76 are bent outwardly at right angles to form short outwardly extending arms 85 that serve as blocking members as explained hereinafter.

According to my invention a pair of locking devices are provided for locking the stops 62 in their outer or withdrawn positions as illustrated in Fig. 7 to permit a joist 52 or 54 to be advanced forwardly along the track 22 after the boards 58 have been nailed thereto as indicated in Figs. 3, 6, 7 and 8. Each locking device comprises a latching bar or bolt 86 adapted for sliding forwardly and rearwardly between a pair of stationary bars or guides 88 fastened between a cover plate 90 and a support or base plate 92 attached to each of the track bars 31 at a position behind the stops 62. The rear portion of each latching bar 86 is recessed to form a forwardly facing shoulder 94 engageable with a trigger member or lever 96

(see Figs. 7 and 8) that is pivotally supported by a vertical pin 98 (Fig. 3) mounted transversely of a window 100 in each support plate 92. An aperture 102 formed in each track bar 31 in registry with the corresponding window 100 permits the inner arm or end 104 of each lever 96 to be moved into and out of the track 22 while the outer arm or end 106 abuts the shoulder 94 of the latching bar 86.

Each locking device also comprises a locking spring 108 that serves to urge the latching bar forwardly into locking position, the spring 108 being connected between the outer end of the corresponding blocking member 85 and a pin 110 projecting outwardly from the rear end of the corresponding latching bar 86. While the stops 62 are in their inner or operative positions (Fig. 8), the forward movement of each latching bar 86 is limited by the abutment of its forward end against the blocking member 85, but when the stops 62 are withdrawn to their outer inoperative positions (Fig. 7), each of the springs 108 forces the corresponding latching bar 86 forwardly into a position between the rear end of the corresponding leaf spring 76 and the adjacent guide bar 31 to retain the stop in its outer, or inoperative, position (Fig. 7). At the same time, the shoulder 94 at the rear of the latching bar 86 forces the outer end of the corresponding lever 96 forwardly, rotating the lever to force the inner end thereof inwardly of the track into a position where it may be tripped by a joist 52 or 54 that is advanced forwardly past the lever. Each of the levers 96 is retained in its operative position by engagement with the rear end 111 of the aperture 102 as clearly shown in Fig. 7.

Also, in accordance with my invention, suitable means are provided for simultaneously forcing the two leaf springs 76 outwardly in the course of the nailing operation. In the particular form of the invention illustrated in Figs. 1 to 8, inclusive, this means comprises a pair of cam bars 112, each of which has a horizontal arm 114 securely attached to the nailing bar 66 and a vertical arm 116 that extends downwardly toward the track. The inner surfaces of the vertical arm 116 are flat and the outer surfaces thereof are inclined inwardly and downwardly forming tapered edges at the lower extremities thereof that lie between the corresponding guide bars 31 and leaf springs 76. With this arrangement, leaf springs 76 are forced outwardly as the nailing bar 66 is lowered during the nailing operation.

In operating the nailing machine in accordance with my invention, the automatic registering mechanism may be prepared for operation initially by drawing the leaf springs 76 outwardly thus permitting the locking springs 108 to force the latching bars 86 forwardly into positions where they retain the stops 62 in their outer, or inoperative, positions and to rotate the inner ends 104 of the levers 96 into the working space of the track 22 between the rails 28 as shown in Figure 7. Thereafter, when the joists 52 and 54 and the boards 58 to be nailed together are assembled in the jig 40, the jig is pushed forwardly on the track from a position starting behind the levers 96.

When the front joist 52 engages the inner ends 104 of the levers 96, these ends are pressed forwardly, rotating the levers to withdraw the latching bars 86 rearwardly, permitting the leaf springs 76 to force the stops 62 into their inner, or operative, positions. As the jig 40 is advanced further, the ends of the leading joist 52 finally

engages the stops 62, halting the movement of the jig and registering the joists and the boards in nailing position directly beneath the nailing members 66 and 68.

While in that position, the nailing machine is operated, the two nailing members 66 and 68 being successively lowered in the manner hereinabove described, forcing nails through the boards 58 into the front joist 52. Simultaneously, the cam bars 112 are lowered, pressing the leaf springs 76 outwardly, withdrawing the stops 62 to their outer, or inoperative positions. At the same time, the latching bars 86 move forwardly to engage the leaf springs to retain them in their outer positions and to rotate the levers 96 to their initial, or operative, positions, preparatory to registering the ends of the rear joist 54 in nailing position. After the boards 58 have been nailed to the front joist, the jig 40 is advanced forwardly and the registering mechanism operates again in the manner described above, the levers 96 being rotated this time by the rear joist 54 to cause the stops 62 to be returned to their operative positions where they register the rear joist in nailing position as the jig advances on track 22. When the boards 58 are nailed to the rear joist 54, the stops 62 are again withdrawn (see Fig. 7) and the levers are again returned to their operative positions by the action of the cam bars 112, preparatory to registering another set of cross pieces in nailing position when another jig is advanced on track 22 as shown by the arrow 60 (Fig. 7).

In an alternate embodiment of my invention, employing a different means for preparing the registering mechanism for operation as illustrated in Figs. 11 and 12, bell cranks 120 are pivotally secured to the uprights 20 for movement about a horizontal axis parallel to the track 22. The upper arm 122 of each bell crank 120 projects inwardly toward the track 22 into a position to be engaged directly by the outer end of the nailing bar 66 as it is lowered. The lower arm 124 of the bell crank 120 extends downwardly and its lower end is connected to the outer end of the corresponding leaf spring 76, through the medium of an adjustable linkage 126, comprising threaded rods 128 and 130, interconnected by a turnbuckle 132. The outer rod 128 is provided with a transverse finger 129 that is journaled to the lower end of the vertical arm 124. The inner rod 130 threadably engages an anchor bar 134 fastened to the free end of the lever 76. With this arrangement, when the nailing operation occurs, the nailing bar 66 presses down upon the upper arm 122 of each bell crank 120 as the nailing bar is lowered, rotating the lower arm 124 outwardly, thus withdrawing the stops 62 to their outer, inoperative, positions, where they are locked by the latching bars 86 in the manner hereinabove explained. This form of my invention has the advantage that it is readily adapted to the adjustment of the spacing between the guide bars 28 without requiring a shifting of a cam bar on the nailing bar, the adjustment being readily accomplished, for example, by substituting threaded arms 130 of suitable length between the turnbuckle and the leaf springs.

In order to adapt my registering mechanism to the accurate registration of joists of different predetermined widths in nailing position, I have provided an alternative form of stop member 140, as illustrated in Figs. 9 and 10. This stop member is in the form of a rectangular block, hav-

ing a threaded connector 142, projecting from one face thereof, the connector being offset from the center of the block. One such block 140 is employed in place of each stop pin 62 of the registering mechanism previously described. By rotating these blocks to various positions and securing them in place by means of nuts 143, the respective faces 144, 146, 148 and 150 of the blocks may be positioned for engagement by a joist, thus establishing different stop positions for the joists. By suitable dimensioning of the block and suitable spacing of the connector from the axis thereof, joists of predetermined dimensions may always be stopped, if desired, with their center lines in the same position relative to the nailing members 66 and 68.

From the foregoing description of my invention, it is apparent that I have provided a simple, low-cost registering mechanism for use in a nailing machine that is positive and reliable in operation and that increases the production capacity of the nailing machine. While my invention has been described with particular reference to its employment with a specific form of pallet in which the joists engage the stops, it is to be understood that the joists may be registered in nailing position in other ways, if desired, such as by arranging for members of the jig itself to engage the stops. Likewise, while my invention has been described with particular reference to the manufacture of pallets in which floor boards are nailed to joists, it is to be understood that it also may be applied to the nailing together of other work pieces. Furthermore, while my invention has been described with reference to the employment of two simultaneously operating stops, it will be clear that only one stop may be used while still retaining many of the advantages of my invention. It is thus apparent that although my invention has been described only with reference to particular forms and applications thereof, my invention is not limited thereto but is capable of a wide variety of mechanical embodiments and applications. It is therefore to be understood that various changes which will now suggest themselves to those skilled in the art may be made in the material, form, details of construction and arrangement of the elements thereof without departing from the principles of my invention. I therefore do not intend to be limited to the specific embodiments of my invention illustrated and described herein, but only by the appended claims.

I claim:

1. In a nailing machine in which a pair of work pieces are advanced along a track to a nailing position in which a nailing member is lowered relative to said track to nail the two work pieces together, the combination therewith of: a stop movable relative to said track between operative and withdrawn positions, the advancement of said work pieces along said track being limited by said stop when in operative position to register said work pieces in nailing position relative to said nailing member, means controlled by advancement of said work pieces toward nailing position while said stop is in a withdrawn position for moving said stop into operative position, and means for withdrawing said stop from operative position to permit said pieces to be advanced beyond said nailing position.

2. In a nailing machine in which a pair of work pieces are advanced along a track to a nailing position in which a nailing member is lowered relative to said track to nail the two work pieces

together, the combination therewith of: a stop movable relative to said track between operative and withdrawn positions, the advancement of said work pieces along said track being limited by said stop when in operative position to register said work pieces in nailing position relative to said nailing member, means controlled by advancement of said work pieces toward nailing position while said stop is in a withdrawn position for moving said stop into operative position, and means controlled by downward movement of said nailing member for withdrawing said stop from operative position to permit said pieces to be advanced beyond said nailing position.

3. In a nailing machine in which a pair of work pieces are advanced along a track to a nailing position in which a nailing member is lowered relative to said track to nail the two work pieces together, the combination therewith of: a stop movable relative to said track between operative and withdrawn positions, the advancement of said work pieces along said track being limited by said stop when in operative position to register said work pieces in nailing position relative to said nailing member, means normally urging said stop into operative position, a locking member movable between operative and withdrawn positions and operative in said operative position to retain said stop in withdrawn position, a trigger member positioned on said track ahead of said nailing position and movable into and out of a cocked position, said trigger member when in cocked position being operated by advancement of said work pieces along said track past said trigger member toward said nailing position to withdraw said locking member from its operative position thereby permitting said stop to move into its operative position, means controlled by downward movement of said nailing member for withdrawing said stop from its operative position whereby said work pieces may be advanced beyond said nailing position after being nailed together, and means also controlled by downward movement of said nailing member for moving said locking member into its operative position and said trigger member into its cocked position.

4. In a nailing machine in which a pair of work pieces are advanced along a track to a nailing position in which a nailing member is lowered relative to said track to nail the two work pieces together, the combination therewith of: a guide bar on said track, a leaf spring secured to said guide bar, a stop attached to the free end of said leaf spring and movable through an opening in said guide bar between operative and withdrawn positions, the advancement of said work pieces along said track being limited by said stop when in operative position to register said work pieces in nailing position relative to said nailing member, a locking member movable between operative and withdrawn positions and operative in said operative position to retain said stop in withdrawn position, said leaf spring holding said stop in operative position when said locking member is in withdrawn position, a second spring urging said locking member into its operative position, a blocking element attached to said leaf spring and positioned thereon to limit the movement of said locking member in a direction toward its operative position when said stop is in its operative position, a trigger member positioned on said track ahead of said nailing position and movable into and out of a cocked position, said trigger member when in cocked position

being operated by advancement of said work pieces along said track past said trigger member toward said nailing position to withdraw said locking member from its operative position whereby said leaf spring moves said stop into operative position, and means controlled by downward movement of said nailing member for withdrawing said stop from its operative position whereby said locking member is moved into its operative position and said trigger member is moved into its cocked position and said work pieces may be advanced along said track beyond said nailing position after being nailed together.

5. In a nailing machine in which a pair of work pieces are advanced along a track to a nailing position in which a nailing member is lowered relative to said track to nail the two work pieces together, the combination therewith of: a guide bar on said track, a leaf spring secured to said guide bar, the free end of said leaf spring being adjacent said nailing position and the secured end thereof being forwardly of said nailing position, a stop attached to the free end of said leaf spring and being horizontally movable through an opening in said guide bar between operative and withdrawn positions, the advancement of said work pieces along said track being limited by said stop when in operative position to register said work pieces in nailing position relative to said nailing member, a locking member movable between operative and withdrawn positions and operative in said operative position to retain said stop in withdrawn position, the rear portion of said locking member being provided with a forward facing shoulder, said leaf spring holding said stop in operative position when said locking member is in withdrawn position, a second spring urging said locking member into its operative position, a blocking element attached to said leaf spring and positioned thereon to limit the movement of said locking member in a direction toward its operative position when said stop is in its operative position, a trigger lever pivotably mounted for movement about a vertical axis, the outer end thereof being positioned for engagement by said shoulder to permit movement of the inner end thereof into and out of a cocked position, said trigger lever when in cocked position being rotated by advancement of said work pieces along said track past said trigger lever toward said nailing position to withdraw said locking member from its operative position whereby said leaf spring moves said stop into operative position, and means controlled by downward movement of said nailing member for withdrawing said stop from its operative position whereby said locking member is moved into its operative position by the action of said second spring and said trigger lever is moved into its cocked position by the action of said shoulder and whereby said work pieces may be advanced along said track beyond said nailing position after being nailed together.

6. In a nailing machine in which a pair of work pieces are advanced along a track to a nailing position in which a nailing member is lowered relative to said track to nail the two work pieces together, the combination therewith of: a guide bar on said track, a leaf spring secured to said guide bar, a stop attached to the free end of said leaf spring and laterally movable through an opening in said guide bar between operative and withdrawn positions, the advancement of such work pieces along said track being limited by said stop when in operative po-

sition to register said work pieces in nailing position relative to said nailing member, a locking member movable between operative and withdrawn positions and operative in said operative position to retain said stop in withdrawn position, said leaf spring holding said stop in operative position when said locking member is in withdrawn position, a second spring urging said locking member into its operative position, a blocking element attached to said leaf spring and positioned thereon to limit the movement of said locking member in a direction toward its operative position when said stop is in its operative position, and a trigger member engageable by said locking member and positioned on said track ahead of said nailing position and movable into and out of a cocked position, said trigger member when in cocked position being operated by advancement of such work pieces along said track past said trigger member toward said nailing position to withdraw said locking member from its operative position whereby said leaf spring moves said stop into operative position.

7. In a nailing machine in which a pair of work pieces are advanced along a track to a nailing position in which a nailing member is lowered relative to said track to nail the two work pieces together, the combination therewith of: a guide bar on said track, a leaf spring secured to said guide bar, a stop attached to the free end of said leaf spring and laterally movable through an opening in said guide bar between operative and withdrawn positions, the advancement of said work pieces along said track being limited by said stop when in operative position to register said work pieces in nailing position relative to said nailing member, said leaf spring holding said stop in operative position when said locking member is in withdrawn position, a locking member movable between operative and withdrawn positions and operative in said operative position to retain said stop in withdrawn position, a second spring urging said locking member into its operative position, a blocking element attached to said leaf spring and positioned thereon to limit the movement of said locking member in a direction toward its operative position when said stop is in its operative position, and means controlled by downward movement of said nailing member for withdrawing said stop from its operative position whereby said locking member is moved into its operative position thereby locking said stop in its withdrawn position so that said work pieces may be advanced along said track beyond said nailing position after being nailed together.

8. In a machine for registering a pair of work pieces as they are advanced along a track to a nailing position in which a nailing member is lowered relative to said track to nail the two work pieces together, a stop, a spring for urging said stop into operative position, the advancement of said work pieces along said track being limited by said stop when in operative position to register said work pieces in nailing position relative to said nailing member, a support member secured to said track, a locking member slidably movable on said support member between operative and withdrawn positions and operative in said operative position to retain said stop in withdrawn position, means for urging said locking member into its operative position, a blocking element for limiting the movement of said locking member when said stop is in operative position, a trigger lever pivotally

mounted on said support member and movable into and out of a cocked position, said trigger lever when in cocked position being operated by advancement of said work pieces along said track past said trigger lever toward said nailing position to withdraw said locking member from its operative position thereby permitting said stop to move into operative position, and means for withdrawing said stop from its operative position whereby said locking member is moved into its operative position and said trigger lever is moved into its cocked position and whereby said work pieces may be advanced beyond said nailing position after being nailed together.

9. In a machine for registering a pair of work pieces as they are advanced along a track to a nailing position in which a nailing member is lowered relative to said track to nail the two work pieces together, a stop, a spring for urging said stop into operative position, the advancement of said work pieces along said track being limited by said stop when in operative position to register said work pieces in nailing position relative to said nailing member, a support member secured to said track, a locking member slidably movable on said support member between operative and withdrawn positions and operative in said operative position to retain said stop in withdrawn position, means for urging said locking member into its operative position, and a trigger lever pivotally mounted on said support member and movable into and out of a cocked position, said trigger lever when in cocked position being operated by advancement of said work pieces along said track past said trigger member toward said nailing position to withdraw said locking member from its operative position thereby permitting said stop to move into operative position.

10. In a machine for registering a pair of work pieces as they are advanced along a track to a nailing position in which a nailing member is lowered relative to said track to nail the two work pieces together, a stop, a spring for urging said stop into operative position, the advancement of said work pieces along said track being limited by said stop when in operative position to register said work pieces in nailing position relative to said nailing member, a support member secured to said track, a locking member slidably movable on said support member between operative and withdrawn positions and operative in said operative position to retain said stop in withdrawn position, means for urging said locking member into its operative position, a blocking element for limiting the movement of said locking member when said stop is in operative position, and means for withdrawing said stop from its operative position whereby said locking member is moved into its operative position so that said work pieces may be advanced beyond said nailing position after being nailed together.

11. In a machine for registering a pair of work pieces as they are advanced along a track of a nailing machine to a nailing position in which a nailing member is lowered relative to said track to nail the two work pieces together, a stop adapted for movement relative to said track between operative and withdrawn positions, the advancement of said work pieces along said track being limited by said stop when in operative position to register said work pieces in nailing position relative to said nailing member, means for urging said stop into operative position, a locking member movable between operative and withdrawn posi-

tions and operative in said operative position to retain said stop in withdrawn position, a trigger member adapted to be positioned on said track ahead of said nailing position and movable into and out of a cocked position, said trigger member when in cocked position being operated by movement of said work pieces along said track past said trigger member toward said nailing position to withdraw said locking member from its operative position thereby permitting said stop to move into operative position, means controlled by downward movement of said nailing member for withdrawing said stop from its operative position whereby said work pieces may be advanced beyond said fastening position after being nailed together, and means also controlled by downward movement of said nailing member for moving said locking member into its operative position and said trigger member into its cocked position.

12. In a machine for registering a pair of work pieces as they are advanced along a track of a nailing machine to a nailing position in which a nailing member is lowered relative to said track to nail the two work pieces together, a stop adapted for movement relative to said track between operative and withdrawn positions, the advancement of said work pieces along said track being limited by said stop when in operative position to register said work pieces in nailing position relative to said nailing member, means for urging said stop into operative position, a locking member movable between operative and withdrawn positions and operative in said operative position to retain said stop in withdrawn position, and a trigger member adapted to be positioned on said track ahead of said nailing position and movable into and out of a cocked position, said trigger member when in cocked position being operated by advancement of said work pieces along said track past said trigger member toward said nailing position to withdraw said locking member from its operative position thereby permitting said stop to move into its operative position.

13. In a machine for registering a pair of work pieces as they are advanced along a track of a nailing machine to a nailing position in which a nailing member is lowered relative to said track to nail the two work pieces together, a stop for limiting the advancement of said work pieces along said track to register said work pieces in nailing position relative to said nailing member, means controlled by downward movement of said nailing member for withdrawing said stop to permit said work pieces to be advanced beyond said nailing position after being nailed together, a locking member movable between operative and withdrawn positions and operative in said operative position to retain said stop in withdrawn position, and means also controlled by downward movement of said nailing member for moving said locking member into its operative position.

14. In a nailing machine in which work pieces of various dimensions are advanced along a track to a nailing position in which a nailing member is lowered relative to a track to nail work pieces together, a stop having a connector eccentrically arranged thereon, and an operating member secured to said connector for moving said stop between operative and withdrawn positions relative to said track, the advancement of said work pieces along said track being limited by said stop when in operative position, said connector being rotatably adjustable relative to said operating

13

member whereby the position to which said work pieces are advanced is adjustable.

15. In a nailing machine in which a pair of work pieces are advanced along a track to a nailing position in which a nailing member is lowered relative to said track to nail the two work pieces together, the combination therewith of: a stop, means for adjusting the position of said stop laterally on said track, said stop being movable relative to said track between operative and withdrawn positions, the advancement of said work pieces along said track being limited by said stop when in operative position to register said work pieces in nailing position relative to

5

said nailing member, and a bell crank mounted for pivotal movement relative to said track, one arm of said bell crank being connected to said stop and the other end being positioned beneath said nailing member whereby said nailing member when lowered engages said other arm to withdraw said stop from operative position.

GROVER C. CABLE.
